UNITED STATES PATENT OFFICE

2,181,431

GRAIN SEPARATOR

Charles C. Ingraham, Minneapolis, Minn., assignor to Hart-Carter Company, Peoria, Ill., a corporation of Delaware

Application June 29, 1936, Serial No. 87,921

3 Claims. (Cl. 209—96)

My present invention provides an improved machine or apparatus for the separation of different kinds of grain and for the separation therefrom of small seeds; and, generally stated, 5 the invention consists of the novel devices, combinations of devices and arrangement of parts hereinafter described and defined in the claims.

More specifically stated, the invention involves 10 a novel co-operative relation of pocketed separating drums and pocketed separating discs. As illustrative of the type of separating disc herein referred to, attention is called to the Carter Patent No. 1,364,247 of January 4, 1921; and as illustrative of the general type of separating 15 drum herein referred to or what may be employed, attention is called to the Ingraham Patent No. 2,015,400 of September 24, 1935.

Both the pocketed drum and pocketed disc types make what is known as a "length separation". However, in the case of the indented or pocketed drum, centrifugal force plays a greater part in making the separation than it does in the case of the pocketed discs. Because of this fact, there are certain separations which can be 20 made more effectively by one or the other of the two types. For example, it is well known that the pocketed drum makes a better separation of barley from oats than does the disc type separator. This is true because the barley, being 25 heavier than oats, will, under the action of centrifugal force, stay in the pockets of the drum until it has reached a much greater height than has the oats. On the other hand, it has been 30 found that the pocketed discs are superior to the pocketed drum for separating wheat from barley and oats or separating small wheat from 35 small seeds and the like. This is true because it is generally recognized that the indented disc is very much more accurate in making separa- 40 tions as to length.

Because of the above characteristics in the two different systems, each system has advantages over the other.

In my Patent No. 2,047,508, issued July 14, 45 1936, I have disclosed and claimed a machine in which material was first passed to pocketed discs and subsequently to an internally pocketed drum or drums. This prior arrangement was, and is, especially adapted for use in grain elevators 50 where it is important that barley be separated from oats as well as from wheat. Moreover, the elevator separation does not require as complete and accurate cleaning of the wheat as is required for mill separation.

55 Wheat flour mill separation, while requiring a

very clean separation of oats, barley and small seeds from the wheat, does not require a separation of the barley from the oats.

My present invention provides a machine that is especially adapted for flour mill separation. 5 In this machine the commingled stock, consisting chiefly of wheat but commingled with oats, barley and small seeds, is first delivered to the internally pocketed or indented drum. I have found that the indented drum with proper sized 10 indents or pockets will make an excellent rough or primary separation of the larger grains or kernels of the commingled mass from the smaller ones; for example, lifting out the small seeds and small wheat in one stream and tailing off the 15 large wheat, oats and barley in another.

These streams are then directed to compartments where they are given accurate disc separations. The stream containing the small wheat 20 and seeds goes to one set of discs where the small seeds are separated from the small wheat, and the stream containing the large wheat, oats and barley goes to another compartment where the discs accurately separate the wheat from the 25 oats and barley.

This novel arrangement makes a more accurate separation of the wheat from oats, barley and small seeds than does the arrangement of my above referred to co-pending application, and also has high capacity. Therefore, it is obvious 30 that this novel arrangement meets the long-felt requirements of the flour mill.

A commercial form of the improved machine is illustrated in the accompanying drawings wherein like characters indicate like parts 35 throughout the several views.

Referring to the drawings:

Fig. 1 is a side elevation of the improved machine, some parts being broken away;

Fig. 2 is an end elevation of the machine looking 40 from right toward the left, in respect to Fig. 1;

Fig. 3 is an end elevation of the machine, looking 45 from the left toward the right, in respect to Fig. 1;

Fig. 4 is a transverse section on the somewhat reduced scale taken on the line 4—4 of Figs. 1 and 5;

Fig. 5 is a view partly in side elevation and 50 partly in diagram in which the machine is somewhat distorted so as to bring into vertical alignment certain parts which, in the machine, are laterally offset, as shown in Figs. 1 and 4;

Fig. 6 is a vertical longitudinal section, some 55

parts being broken away, taken on the line 6—6 of Fig. 7;

Fig. 7 is a fragmentary section taken on the line 7—7 of Fig. 6;

5 Fig. 8 is a fragmentary section taken on the line 8—8 of Figs. 5 and 6; and

Fig. 9 is a fragmentary section taken on the line 9—9 of Figs. 5 and 6.

10 Fig. 10 is a diagrammatical view showing the flow of commingled stock to and through the drum and disc separating elements of this compact machine.

The various parts of the machine illustrated are mounted within a casing shown as made up 15 of a sheet metal body 10 and end plates 11. In this improved machine the internally pocketed or indented drum or cylinder is mounted in the upper portion of the casing, and the discs are mounted in the lower portion of said casing. The 20 drum structure and associated parts may vary in their construction and details of arrangement, may be and advisably are of the construction and arrangement illustrated in my prior Patent No. 2,015,400 of September 24, 1935. The separating 25 discs, as before stated, are of the type disclosed and broadly claimed in the Carter patents identified. One of the head plates 11, as shown in the left hand plate, is formed or provided with a large elbow-like pocket 13 and affords an 30 intake passage for the material to be delivered to the machine.

The other head plate 11, to wit: as shown, the right hand member, is formed with an inverted pocket-like portion 14 that affords a discharge 35 passage. Extended through the casing and the pockets 13 and 14 and journaled in suitable bearings on the walls thereof is a long shaft 15 provided with a spiral blade 16. A bearing sleeve 17 is extended through the outer wall of the 40 pocket 14 and the right hand end of shaft 15 is journaled in and extended through this sleeve. Sleeve 17, by radial web, carries a large collar 18 on which is journaled an annular gear 19. Collar 18 is relatively non-rotary, but preferably capable of oscillatory adjustments for a purpose 45 which will hereinafter appear.

The internally indented drum or cylinder 20, at its receiving end, is provided with and fixed to a spider-like head 21 that is keyed or otherwise rigidly secured to the shaft 15 so that said drum will be rotated with said shaft. At its 50 other end, the drum 20 is rigidly secured to the rotary annular gear 19, and inward of said gear, said drum is provided with large circumferentially spaced discharge passages 22.

The conveyor, made up of the shaft 15 and its spiral blades 16, works in a long catch trough 23, which, at its right hand end, has a discharge neck projected into and rigidly secured to the collar 18 so that said trough can be given oscillatory 55 adjustments by movements of said collar. At its left hand end, trough 23 is provided with a suitable bearing 24 journaled on, but not rotated with, shaft 15.

60 Further describing the structure illustrated in my said prior Patent No. 2,015,400, the numeral 25 indicates a feed-screw that works near the bottom of the drum 20 and is journaled in bearings 26 secured to and depending from the trough

70 23. At its right hand end, as shown in Fig. 5, the shaft of feed-screw 25 is provided with a pinion 27 that meshes with and is driven from the annular gear 19. As a means for imparting oscillatory adjustments to the collar 18, and hence 75 to the feed trough 23, a worm gear 28 is at-

tached to said sleeve 17 for adjustments therewith, and this worm gear 28 is engaged by the manually operated worm 29 mounted on the outer wall of the discharge pocket 14, as shown in Figs. 2 and 5. At its left hand end, shaft 15 is shown as provided with a sprocket wheel 30.

The body shell 10 of the casing is shown as provided with openings 31 to afford means for carrying off the dust or like particles if desired.

10 Mounted within the shell 10 of the casing and extended from one head plate to the other and located below the drum 20, but above the discs, is a trough 32, see particularly Figs. 1, 4 and 5. A feed-screw 33 works in this trough 32, and its shaft is extended through suitable bearings on 15 the head plates of the casing. At one end, see Figs. 2 and 5, the shaft of feed-screw 33 is provided with a driving pulley 34, and at its other end, see Figs. 3 and 5, said shaft is provided with a driving sprocket 35. The tailings delivered 20 from drum 20 through openings 22 are delivered into the right hand end of receiving trough 32 through short neck or discharge conduit 36, see particularly Fig. 5.

25 The separating discs are located near the lower portion of the casing and are secured to a long shaft 37 that is extended through suitable bearings on the head plates 11. For important reasons, the discs are arranged in two groups, the first group being indicated by the character 38, 30 and the second by the character 38a. The discs 38 have pockets that are smaller than the discs 38a. For the particular separation for which this machine has been designed, the pockets of 35 the discs 38 will be of a size to receive and carry up small seeds, but to reject small or broken wheat; and the pockets of the discs 38a will be of a size to pick up and lift large wheat, but to reject oats and barley, for example.

30 The discs work in a hopper-like bottom-forming structure or container 39, see particularly Figs. 4, 5, 6 and 7. This hopper-like structure extends from one head plate to the other, but is divided into compartments a and b by a partition plate 40. The discs 38 work in the compartment a while the discs 38a work in the compartment b. In the particular structure illustrated, the hopper 39 is depressed to form a trough-like portion 41 in which is located a manually operated clean-out screw 42. At one side of the hopper-like bottom 39 is a long trough 43 that is extended from one head plate 11 to the other and by the partition 40 is divided into compartments c and d. Extended through the trough 43 and journaled in suitable bearings on the head plates 11 is a shaft 44 that carries a left hand spiral blade 45 that works in the compartment c, and a right hand spiral blade 45a that works in the compartment d. Opening through the bottom of the feed trough 43 from the compartment 60 c is a discharge spout or opening 46, and opening through the bottom of said trough from the compartment d is a discharge spout for opening 46a. At its right hand end, as shown in Figs. 1, 4, and 5, shaft 44 is provided with a sprocket 47. 65 The disc-carrying shaft 37, at its right hand end, is provided with a sprocket 48, and at its left hand end with a sprocket 49.

In respect to Fig. 4, the discs are assumed to be rotated in a clockwise direction. Located at 70 the delivery side of the disc, just above the conveyor 45, is a long trough 50, see Figs. 4, 5, 6 and 7, that extends from one head plate to the other, and by the partition 40 is divided into one section 75 for the compartment a and into another section

for the compartment *b*. Within the compartment *a* the trough 50 is provided with closely associated cover plates or sections 51 that are hingedly connected to the outside wall of trough 50; and within the compartment *b* said trough is likewise provided with similar hinged cover plates or sections 51a.

Here it should be noted that the outer wall of trough 50 is spaced from the adjacent wall of the casing 10 so as to afford passages 52 that lead from the compartment *a* to the compartment *c* and from compartment *b* to compartment *d*. Also, it will be noted that the cover plates, or any desired number thereof, can be turned into full line position, see Figs. 6 and 7, over trough 50 so as to deflect grain into passage 52 or may be set, as shown by dotted lines in Fig. 7 and as in Fig. 4, so as to deliver the grain into said trough 50.

20 A shaft 53 is extended through the entire trough 50, is journaled in suitable bearings on the end plates 11, and is provided with spiral conveyor blades 54 and 54' working, respectively, in those portions of trough 50 that are in the compartments *a* and *b*.

25 The oblique upper portion of the inner wall of the trough 50, adjacent to the right hand end plate 11 and adjacent to the partition 40, is cut away, respectively, to form discharge ports 53a and 53a', see particularly Figs. 5, 8 and 9.

30 Extending downward from the depending end of the inverted pocket 14 is a delivery spout 55 that terminates in a discharge end 55a located just inside of the right hand head plate 11, see Fig. 5.

35 Also, by reference to Fig. 5, it will be noted that the bottom of the trough 32 is intermediately cut away at 56 to afford a delivery passage from the trough that extends over about one-half of the pocketed separating discs 38a.

40 In the partition 40, see Figs. 5 and 9, is a discharge port 57 open to compartment *a* that opens into an overflow discharge spout 58, the lower end of which delivers into that portion of the trough 43 that is within the compartment *d* at the left of the partition 40. In the left hand end plate 11 is a discharge port 59, see Figs. 4 and 5, that leads to a discharge spout 60.

45 Referring now particularly to Figs. 2, 3 and 5, the numeral 61 indicates a sprocket chain that runs over the sprocket 48 and over the sprocket 62 on the conveyor shaft 44. A shorter sprocket chain 63 runs over the sprocket 47 of shaft 44 and over a similar sprocket 64 on the conveyor shaft 53. As shown, the above noted elements 47 and 48, 61, 62, 63 and 64 are within the housing 65 secured on the right hand head plate 11.

50 A sprocket chain 66 runs over the sprockets 30, 35 and 49 and under a chain tightening sprocket 67 joined to a suitable bearing 68 on the left hand end plate 11. As shown, the said portions 30, 35, 49, 66 and 67 are located in a housing 69 attached to the left hand head plate 11.

Operation

65 In the following described operation of the machine the commingled stock, to be separated thereby, will be assumed to consist of large wheat, small wheat, oats and small seeds, but in which stock the large wheat is in the majority.

70 The following operation will be most readily understood by directing attention particularly to Fig. 5, but, for the details of construction, attention will be called also frequently to Figs. 4, 6, 7, 8 and 9.

The mixture may also contain other grains, such as barley, which, in the following operation, will be treated but lightly inasmuch as the handling of the barely will follow closely the handling of the oats. This commingled stock will be fed into the rotary drum 20 through the intake pocket 13, and by the screw 25 will be distributed quite evenly along the bottom of the drum. Under rotation of the drum, which is assumed to be in a clockwise direction in respect to Fig. 4, the small wheat and small seeds such, for example, as cockle, mustard, and the like, will be picked up by the pockets of the drum and carried to a point where, when discharged, they will drop into the trough 23, while the large wheat, oats and the like, will be rejected by the pockets or, at any rate, will fall back to the lower portion or bottom of the drum. Before the commingled stock has been fed to the delivery end of the drum, all, or substantially all of the small or broken wheat and small seeds will have been lifted and discharged into the trough 23, and from thence by the screw 16 will be discharged into the spout 55 and delivered into the receiving end of the compartment *a* in which are located the first group of pocketed separating discs 38. The large wheat and the oats, as tailings, will, under the action of the spiral conveyor 25, be discharged through conduit 27 into the trough 32. The separating actions performed by the drum and by the discs will take place simultaneously, but as the groups of discs 38 and 38a perform somewhat different functions, the separation that takes place in compartment *a* and in compartment *b* will be separately described.

Action in compartment (a)

As the discs 38, with relatively small pockets as compared with the discs 38a, revolve through the body of commingled small wheat and smaller seeds, the discs at the right, in respect to Fig. 5, at first will pick up only the small seeds, but toward the left a point will be reached where there will be some commingled small wheat and small seeds. Hence, the cover plates 51 at the right will be turned over and close the underlying portion of the trough 50, as shown by dotted lines in Fig. 8, so that the lifted small seeds will be deflected by said down-turned cover plates and delivered into the compartment *c* of trough 43. The cover plates 51 at the left, in respect to Fig. 5, will be turned back, as shown by full lines in Figs. 4 and 8, thereby causing commingled small wheat and smaller seeds to be delivered into that section of trough 50 that is within compartment *a*.

55 Under the action of the spiral conveyor 54 on shaft 53, the commingled small wheat and seeds will be delivered to the right hand end of trough 50 where it will back up, and by the delivery of the conveyor, it will be crowded through port 53a, see Figs. 5 and 8, and delivered back into compartment *a* for reseparation under the action of the discs 38.

60 Under the action of the spiral conveyor 45 on shaft 44, the small seeds will be fed to the right and discharged through spout or discharge opening 46.

65 The small or broken wheat, separated from the small seeds, will accumulate in the compartment *a* as tailings until they will overflow through port 57 and be delivered through spout 58 into that portion of trough 43 that is in compartment *d*, or to a point outside of the housing or body 10 as indicated in dotted lines in Fig. 9 at 58a.

Action in compartment (b)

The commingled large wheat and oats, freed from small wheat and smaller seeds delivered as tailings from the drum and into trough 32, will, under the action of the spiral conveyor 33, be discharged into the right hand portion of compartment b.

The pockets of the group of discs 38a, as indicated, are of a size to pick up and lift large wheat, but to reject oats or barley or the like, if any. The discs 38a at the right for a certain distance will pick up large wheat, but a certain point will be reached where the discs will pick up and lift some barley or possibly oats, as well as wheat.

By adjustments of the cover plates 51a, a proper point of separation may be found. When the cover plates 51 are turned over the underlying port of trough 50, as shown by full lines in Fig. 7, the lifted, clear or clean wheat will be deflected and delivered into that portion of trough 43 that is within compartment d, and under the action of spiral conveyor 45a will be discharged through the port of outlet 46a.

Certain of the cover plates 51a at the left will be turned back, as shown by full lines in Fig. 9, so that commingled wheat and barley will be delivered into that portion of trough 50 that is within compartment b; and such commingled wheat and barley will, by spiral conveyor 54', be delivered against partition 49 where it will bank up and, by the delivery end of said conveyor, discharge through port 54a back into compartment b for recleaning or separation under the action of discs 38a.

The oats and barley or the like will accumulate in the bottom compartment b at the left hand end thereof and will bank up until they overflow through port 59 into discharge spout 60.

Thus is noted the manner in which the main stock is first divided into relatively small and relatively large materials, with one division in this particular instance being small or broken wheat and small seeds, and the other division consisting of large wheat and oats or the like. We have also traced the manner in which the small seeds are finally separated from the small or broken wheat; the manner in which the large wheat is separated from the oats or the like; and the manner in which the clean small wheat is recommingled with the clean large wheat.

If not desired to recommingle the small wheat with the large wheat, discharge spout 58 could be made to extend through a wall of the housing or body 18 as indicated in dotted lines in Fig. 9.

What I claim is:

1. A self-contained flour mill separator for commingled stock consisting chiefly of wheat but mixed with oats, barley and small seeds, comprising

an internally pocketed rotary drum separator arranged to receive the commingled stock and to rapidly separate the stock into at least two batches according to the size of the grains of the stock under treatment, separate compartments each arranged to receive a separated batch of the stock delivered from said drum, and pocketed separator discs of relatively low capacity but of relatively high selectivity for flour mill separation mounted in said separate compartments for rotation with said drum, whereby the small wheat is accurately separated from the small seeds and the large wheat from the oats and barley by said discs at substantially the same rate of high capacity as that of the initial low selectivity drum separator.

2. A method of treating commingled stock consisting chiefly of wheat mixed with oats, barley and small seeds, for flour mill use, which comprises the steps of introducing the stock into an internally pocketed rotary drum separator, rotating said drum to divide the stock into at least two batches according to the size of the grains so that each batch contains grains of substantially uniform size, delivering the separated batches of grain into separate compartments for further separations by disc separators of relatively low capacity but of relatively high selectivity for flour mill separations, and driving said disc separators with said drum separator whereby the small wheat is accurately separated from the small seeds and the large wheat from the oats and barley at substantially the same rate of high capacity as that of the initial low selectivity drum separator.

3. A self-contained flour mill separator for a commingled stock, of large and small wheat, oats, barley and small seeds, comprising a supporting frame, an internally pocketed rotary drum separator journaled in said frame and arranged to receive the commingled stock for rapid separation of the stock into at least two batches according to the size of the grains of the stock under treatment, variably adjustable separation means in the drum separator for controlling the division of stock so that it will be separated into substantially equal size batches, separate compartments mounted in said frame and each arranged to receive a separated batch of the stock from said drum, and pocketed separator discs of relatively low capacity but of relatively high selectivity for flour mill separation mounted in said separate compartments for rotation with said drum, whereby the small wheat is accurately separated from the small seeds and the larger wheat from the oats and barley by said discs at substantially the same rate of high capacity as that of the initial low selectivity drum separator.

CHARLES C. INGRAHAM. 60
